FORGING MACHINE

Wade H. Wineman, Michigan City, Ind., assignor
to Joy Manufacturing Company, a corporation
of Pennsylvania

Application April 11, 1944, Serial No. 530,509

27 Claims. (Cl. 76—5)

1

My invention relates to forging machines, and more particularly to forging machines adapted especially for use in sharpening and forming drill bits.

During the forging of heated articles, it is desirable that means be provided for cooling the portions of the forging machine supporting and holding the article in place so that these portions will not be softened by the heat to a point where they will be deformed by the forging action. It is also desirable that portions of the heated article be cooled before the forging action takes place so as to stiffen up the metal in these portions and confine the forming of the metal to the portions of the article to be shaped. In order that the desired cooling effects may be obtained, I have provided in the forging machine of my invention improved means for delivering a cooling fluid to parts to be cooled; and, in order that the delivery of cooling fluid and the operation of the forging machine may take place at the proper time, I have provided improved means for controlling the flow of cooling fluid and the flow of operating fluid to the hammer piston of the machine. To increase the efficiency of my forging machine I have also provided improved means for releasing the article from its supporting means and ejecting the article from its supported position after the forging operation has been completed.

An object of my invention is to provide an improved forging machine. Another object of my invention is to provide a forging machine having improved means for cooling the parts of the machine supporting a heated article to be forged. Still another object of my invention is to provide an improved forging machine having improved means for controlling the supply of a cooling fluid and the flow of operating fluid to the machine. Yet another object of my invention is to provide a forging machine having a forging hammer which is movable to operating and non-operating positions, and having improved means for moving the hammer to such positions. Still another object of my invention is to provide an improved forging machine having control means including a single operating member for adjusting the position of the forging hammer, controlling the flow of operating fluid to the machine, and controlling the flow of a cooling fluid to the supporting means for the article to be forged. Another object of my invention is to provide a forging machine having improved means for releasing the forged article from its supporting means and ejecting the article from its supported

2

position. Yet another object of my invention is to provide an improved forging machine having an adjustable hammer motor and means for adjusting the same to facilitate the insertion and removal of an article to be forged, also having operating-fluid supply means for the motor, cooling-fluid supply means for the article supporting means, means for ejecting the article after it is forged, and means including a single control member for controlling the operation of each of said means. These and other objects of my invention will appear more fully in the course of the following description.

In the accompanying drawings, I have shown for purposes of illustration one embodiment which my invention may assume in practice.

In these drawings:

Fig. 1 is a front elevational view of my improved forging machine.

Fig. 2 is a side elevational view of the machine shown in Fig. 1.

Fig. 3 is an enlarged vertical sectional view taken on the plane of the line 3—3 of Fig. 1.

Fig. 4 is a vertical sectional view taken on the plane of the line 4—4 of Fig. 3.

Fig. 5 is a horizontal sectional view taken on the plane of the line 5—5 of Fig. 4.

Fig. 6 is a sectional view taken on the plane of the line 6—6 of Fig. 4.

Fig. 7 is a sectional view similar to that of Fig. 3 but showing parts in different positions.

Fig. 8 is a side elevational view showing the fluid supply control means for the forging machine.

Fig. 9 is an enlarged detail sectional view taken on the plane of the line 9—9 of Fig. 8.

Fig. 10 is an enlarged detail sectional view taken on the plane of the line 10—10 of Fig. 8.

Fig. 11 is an enlarged sectional view showing one of the fluid supply control valves and taken on the plane of the line 11—11 of Fig. 5.

In the illustrative embodiment of my invention there is shown a forging machine, generally designated 1, having a hollow base frame 2 on the top of which a platform 3 is connected, as by bolts 4, and slidably mounted on the platform 3 is a standard 5 for a forging hammer, generally designated 6. The platform 3 is provided with guideways 8 receiving guide portions 9 on the standard for guiding the movements of the forging hammer over the platform. Formed on the lower side of the standard is a rack 10 projecting into a recess 11 in the platform and engageable at its ends with surfaces 12 and 14 on the platform for limiting move-

ment of the forging hammer into its operating and non-operating positions, respectively. Projecting through an opening 16 in the platform is a gear segment 17 meshing with the rack 10, and the gear segment is fixed to a shaft 18 extending transversely of the base frame 2 and rotatably supported at its ends in the side walls of the frame. At one end of the shaft 18, as shown in Figs. 8 to 10, is an arm 20 having a hub portion 21 fixed to the shaft, as by a key 22. Pivotedly mounted on the shaft 18 is an operating lever 24 which extends, as shown in Fig. 9, between flanges 25 and 26 formed on the arm 20, and a spring 28 acting between the flange 26 and the operating lever tends to hold the arm and the lever in spaced angular positions relative to each other. As the lever 24 is swung upwardly it acts against the flange 25 and swings the arm 20 which, in turn, rotates the shaft 18 in a counter-clockwise direction, as viewed in Fig. 8. The gear segment 17 rotates with the shaft 18 and moves the standard 5 rearwardly on the platform 3. When the lever is swung downwardly toward its horizontal position, as shown in Fig. 8, it acts through the spring 28 to swing the arm 20 and rotate the shaft 18 in a direction to move the forging hammer toward its operating position. After the hammer has been moved to its operating position and the front end of the rack 10 engages the surface 12 resisting further forward movement, the lever 24 may be swung a short distance relative to the arm 20 against the force of the spring 28.

Fitting within an opening 30 in the platform 3 and resting on a thickened wall portion 31 of the base frame 2 is a die block 32 having an opening 33 within which the article to be forged, in this case a drill bit 34, is received. Extending through an opening 36 in the wall portion 31 into the opening 33 in the die block is an elongated support member or holder 37 having a threaded end portion 38 to which the drill bit 34 is adapted to be connected. Formed on the holder member 37 adjacent the portion 38 is an annular flange 39 engageable with a wear bushing 40 which supports the member during forging. The portion of the member 37 below the flange 39, shown herein as being of hexagonal shape, projects through the opening 36 into the open center of the frame 2, the opening 36 being of sufficient size to permit free rotation of the member therein. Connected to the lower side of the wall portion 31 is a frame 42 supporting a ratchet mechanism, generally designated 43, operatively engaging the member 37.

This ratchet mechanism comprises a pawl carrier 45 which is rotatably supported in bearings 47 and 48 carried by the wall portion 31 and the frame 42, respectively, and extending through the pawl carrier is an opening 49 through which the member 37 projects. The opening 49 is of the same shape as the body portion of the member 37 and receives the latter with a fit sufficiently close to prevent relative rotation therebetween. Surrounding the pawl carrier is a ratchet member 50 having teeth 51, as shown in Fig. 5, which are engaged by pawls 52 carried by the pawl carrier and pressed outwardly by spring pressed plungers 53. The arrangement of the pawls is such that the pawl carrier is rotated with the ratchet 50 when the latter rotates in a clockwise direction, as viewed in Fig. 5, but remains stationary with the pawls sliding over the teeth when the ratchet rotates in the opposite direction. It will be noted that the direction of rota-

tion of the pawl carrier by the ratchet is such as to effect at least partial release or loosening of the threaded connection between member 37 and the drill bit.

5 In order to effect a rotation of the ratchet 50 there is provided on the latter gear teeth 55 with which a gear segment 56 meshes. The gear segment 56 is pivotally mounted, as shown in Fig. 4, on a pin 58 bolted to the side of the base 2, and an operating lever 59 formed integral with the gear segment, extends through an opening 60 in the base 2 and is provided with a foot pedal 61 adapted to be actuated by the operator. A spring 62 connected to the base 2 and the lever 59 normally holds the latter in such a position that the gear segment 56 may be operated to actuate the ratchet mechanism. At times the forged drill bit may be so tightly connected to the member 37 that additional means are needed to loosen it. To 10 take care of these conditions I have provided a cylinder 64 connected, as shown in Fig. 5, to an inside wall of the base 2 and containing a reciprocable piston 65 having a piston rod 66 which is pivotally connected by a link 67 to the gear segment 56. A fluid supply connection 69 opens into the cylinder 64 at the outer end of the latter.

In order that the lower portion of the drill bit and the threaded portion of the member 37 may be cooled, I have provided a bore 71 extending 15 from the lower end of the member 37 longitudinally through the latter into the threaded portion 38. Arranged below the lower end of the member 37 and connected to the side of the base frame 2, as by bolts 72, is a trough-like member 35 73 having a drain connection 74. Extending upwardly within the trough of the member 73 is a pipe section 76 which passes through the bore 71 to a point adjacent the threaded portion 38 of the member 37. The pipe section 76 is somewhat 20 smaller than the bore 71 in diameter so as to provide a space between it and the walls of the bore through which cooling liquid may escape to the trough of the member 73. The lower end of the pipe section 76 is connected in communication 25 with a passage 77 in the member 73, and a fluid supply connection 79 is arranged to deliver fluid to this passage.

To effect an ejection of the forged drill bit from the die block I have provided a bell crank lever 81 which is pivotally supported by a shaft 82 extending transversely of the base frame 2. The lever has an arm 83 engageable with the lower end of the member 37 and an arm 84 carrying at its outer end a roller 85. Attached to the 30 shaft 18, as by a key 86, is a cam member 87 having a portion 89 which is engageable with the roller 85 when the shaft 18 is rotated to position the standard 5 at the rearward end of the platform 3. When the cam portion 89 engages the 35 roller 85, the bell crank lever 81 swings about the shaft 82, lifts the member 37 and ejects the drill bit from the die block 32. The cam member has another cam portion 98 engageable by the roller 85 for holding the bell crank lever in a position 40 which permits the member 37 to drop through the opening 36 until it is supported by the wall portion 31.

The forging hammer 6 may be of any type desired but, for purposes of illustration, I have 45 shown a forging hammer of the piston hammer type, such as is shown in Patent 1,440,807, issued to me on Jan. 2, 1923, the same comprising a cylinder 92 having a piston 93 reciprocable therein and adapted to deliver its blow through a striking 50 bar 94. The pressure fluid is supplied from a con-

nection 95 through a valve mechanism, not shown, to the upper end of the cylinder 92, and is exhausted from the cylinder through an exhaust passage 96 which communicates with the upper end of the cylinder under the control of the valve mechanism and with the lower end of the cylinder through a port 97. Arranged in a recess 98 beneath the striking bar is a die block 99 which is normally held by springs 100 in a raised position free from the lower die block 32 and the work. In order that the upper die block may be held against the work during the operation of the forging machine, there is provided a sleeve 101 reciprocable in a bore 102 and having pressure fluid supplied to its upper end through a passage 103 which communicates freely with the connection 95. The forging hammer and its operation will not be described herein in detail since its construction and operation form no part of the present invention.

Attached to the side of the platform 3 and the base frame 2, as shown in Figs. 4 and 8, are valve devices 104, 105 and 106. The valve device 104 controls communication between a cooling fluid supply connection 108 and the pipe connection 79. This valve device includes a valve stem 109 which is engageable by the lever 24, and is actuated by the lever to close the valve when the lever is swung to its uppermost position. When the lever is swung away from the valve stem, the valve opens to permit fluid to flow to the pipe 79. The valve device 105 controls the connection between a pressure fluid supply line 112 and the connection 95 leading to the forging hammer. This valve device has a valve stem 113 which is engageable by the lever 24 and is adapted to be actuated by the latter to open the valve when the lever is swung below its horizontal position against the action of the spring 28. The valve device 106 controls the connection of the pipe 69 leading to the cylinder 64 with a pressure fluid supply line 115 and with a suitable vent. This valve device includes, as shown in Fig. 11, a valve casing 116 containing a valve piston 117 which has a reduced portion 118 between its ends. A stem 119 projects from the piston through one end of the casing 116, and a spring 120 acts against the other end of the piston to hold the piston normally in such position that its stem projects outwardly from the casing. The pipe connection 69 communicates with the space 121 surrounding the reduced portion of the valve piston, and a vent port 122 and the fluid supply connection 115 open through the casing at opposite sides of the connection 69. When the valve piston is in a position with its stem projecting from the casing, the vent port 122 is connected to the connection 69 through the space 121 and the fluid supply connection 115 is blocked off by the piston. When the valve piston is moved inwardly against the force of the spring 120, the vent port 122 is blocked off by the piston and the supply connection 115 is connected to the connection 69. A bell crank lever 124 pivotally connected to the side of the base frame 2 has an arm portion 125 engageable with the valve stem 119, and an arm portion 126 which may be grasped by the operator to actuate the lever.

When it is desired to perform a forging operation, the lever 24 is swung to its vertical position laterally moving the forging hammer rearwardly on the platform 3 out of alignment with the stationary die block and actuating the bell crank lever 124 to lift the support member 37 into the position shown in Fig. 7. With the lever in this

position, the valve 104 is held closed to cut off the flow of cooling fluid to the pipe 79. A heated drill bit is then connected to the threaded portion 38 of the support member 37 and the lever 24 is swung downwardly to move the forging hammer toward its operating position. As the lever is moved away from the valve 104, the latter opens so that cooling fluid flows through pipe 79, the passage 77 and the pipe section 76 into the bore 71 of the support member 37. As the forging hammer moves laterally forwardly on the platform 3 to its position of alignment with the stationary die block, the portion 89 of the cam 87 moves away from the roller 85, and the bell crank lever 81 swings about its shaft 82 permitting the member 37 to drop through the opening 36 until the drill bit is received within the opening 33 of the die block 32. The cooling fluid delivered from the pipe section 76 then enters the portion of the bore 71 within the threaded portion 38 and cools the latter and the lower portion of the drill bit. The cooling fluid entering the bore 71 flows downwardly about the pipe section 76 into the trough member 73 and is carried away through the drain connection 74.

When the forging hammer reaches its operating position in alignment with the stationary die block, the arm 20 stops in the position shown in Fig. 8 since it is fixed to the shaft 18. The operating lever 24 may then be swung downwardly relative to the arm 20 against the force of the spring 28 so as to actuate the valve stem 113 and connect the pressure fluid supply connection 112 to the connection 95 leading to the cylinder 92 of the forging hammer. Pressure fluid from the connection 95 enters the passage 103 where it flows to the upper end of the sleeve 101 and forces the latter downwardly moving the die block 99 into engagement with the lower die block 32. The pressure fluid also acts on the piston 93 and effects a reciprocation of the latter to deliver blows to the die block 99 through the striking bar 94. The die block 99 operates on the drill bit to provide the desired forming action, and, after this has been completed, the lever 24 is swung upwardly permitting the valve device 105 to close and then, on further upward movement, moving the forging hammer rearwardly on the platform 3. Before the forging hammer is moved to its most rearward position, the operator steps on the pedal 61 to actuate the gear segment 56 and rotate the member 37 through the ratchet mechanism 43. The forging of the drill bit causes the latter to be pressed within the lower die block with sufficient force to hold it against rotation, and the rotation of the member 37 causes the latter to be at least partially unthreaded from the bit. If additional force is needed to actuate the gear segment 56, the operator may swing the bell crank lever 124 about its pivot to actuate the valve device 106 for connecting the pressure fluid supply line 115 in communication with the pipe connection 69. Pressure fluid then flows through the pipe connection 69 to the cylinder 64 where it acts on the piston 65 and moves the latter in a direction to effect a rotation of the ratchet mechanism in a direction to release the member 37 from the drill bit. After the member 37 has been released from the bit, the lever 24 may be swung upwardly to its vertical position bringing the portion 89 of the cam member 87 into engagement with roller 85 and effecting a swinging of the bell crank lever 81 in a direction to lift the member 37 and eject the drill bit from the die block 32. The completed drill bit

may then be removed from the holder member 37.

As a result of my invention it will be noted that there is provided an improved forging machine in which portions of the supporting means for the article to be forged, as well as portions of the article itself, are cooled before any forging action takes place. The forging hammer is movable toward operating and non-operating positions, and, on movement toward its non-operating position, the forged article is automatically ejected from the die. A control means including a single operating member controls the positioning of the hammer, the flow of cooling fluid, the flow of operating fluid for the hammer, and the ejecting of the forged article from the die. Because of the control means provided there is assured an operation of the machine to perform its different functions at the proper time, and the efficiency of the machine is increased.

While I have in this application specifically described one form which the invention may assume in practice, it will be understood that this form of the same is shown for purposes of illustration, and that the invention may be modified and embodied in various other forms without departing from its spirit or the scope of the appended claims.

I claim:

1. In a forging machine, in combination, a forging hammer, means supporting said hammer for movement into operating and non-operating positions, means including a lever for moving said hammer on said supporting means, means for supporting an article to be forged in a position to be operated upon by said hammer when the latter is in its operating position, means for supplying a cooling fluid to said article supporting means, said last mentioned means including a valve member movable to an open position when said lever is actuated to move said hammer toward its operating position, and means including an element adapted to be actuated by said lever after said hammer has been moved to its operating position for effecting operation of the latter.

2. In a forging machine, in combination, a forging hammer, means supporting said hammer for movement into operating and non-operating positions, means including a lever for moving said hammer on said supporting means, a die block adapted to receive a drill bit to be forged, a member movable relative to said die block and cooperating with the latter for supporting the drill bit in a position to be forged, means for supplying a cooling fluid to the portion of said member adjacent the drill bit, said last mentioned means including a valve member movable to an open position when said lever is actuated to move said hammer toward its operating position, and means including an element adapted to be actuated by said lever after said hammer has been moved to its operating position for effecting operation of the latter.

3. In a forging machine, in combination, a forging hammer, means supporting said hammer for movement into operating and non-operating positions, means including a lever for moving said hammer on said supporting means, a die block adapted to receive a drill bit to be forged, a member movable relative to said die block and cooperating with the latter for supporting the drill bit in a position to be forged, means for supplying a cooling fluid to the portion of said member adjacent the drill bit, said last mentioned means including a valve member movable to an open position when said lever is actuated to move said hammer toward its operating position,

means including an element adapted to be actuated by said lever after said hammer has been moved to its operating position for effecting operation of the latter, and means for moving said member relative to said die block and ejecting the drill bit after it has been forged, said last mentioned means including an element actuated on movement of said hammer away from its operating position.

10 4. In a forging machine, in combination, a fluid actuated hammer motor, means for delivering operating fluid to said motor, valve means for controlling the flow of operating fluid through said fluid delivering means, means for supporting an article to be forged in a position to be percussively acted on by said hammer motor, means for delivering cooling fluid to said supporting means to maintain portions of the article cool during the forging operation, valve means for controlling the flow of fluid through said cooling fluid delivering means, and means for operating both of said valve means including an operating element common to both valve means for effecting operation thereof in a predetermined sequence.

20 5. In a forging machine, in combination, a hammer motor, a movable die percussively actuated thereby, a cooperating relatively stationary die adapted to receive an article to be forged, means for moving said hammer motor bodily laterally into and out of aligned operating position with respect to said stationary die, control means actuated by an element of said motor moving means for automatically effecting operation of said hammer motor only when the latter is in its operating position in alignment with said stationary die, and means also actuated by an element of said motor moving means and automatically effective only when said hammer motor has assumed its non-operating position out 30 of alignment with said stationary die for releasing the forged article from said stationary die.

6. In a forging machine, in combination, a hammer motor, a movable die percussively actuated thereby, a cooperating relatively stationary die adapted to receive an article to be forged, means for moving said hammer motor into and out of its operating position with respect to said stationary die, control means actuated by an element of said motor moving means for automatically effecting operation of said hammer motor only when the latter is in its operating position, and means also actuated by an element of said motor moving means and automatically effective only when said hammer motor has assumed its non-operating position for releasing the forged article from said stationary die, said motor-moving means, said control means and said releasing means having a common movable actuator for effecting, upon movement thereof 40 in one direction, motor movement, interruption of motor operation and article release in a predetermined sequence.

7. In a forging machine, in combination, a hammer motor, a movable die percussively actuated thereby, a cooperating relatively stationary die adapted to receive an article to be forged, means for moving said hammer motor into and out of its operating position with respect to said stationary die, means for supporting the article 50 to be forged with respect to said stationary die in a position to be operated upon by said movable die when said hammer motor is in its operating position, control means actuated by an element of said motor moving means and automatically effective only when said hammer motor is in its

operating position for effecting operation of said hammer motor, and means also actuated by an element of said motor moving means and automatically effective only when said hammer motor assumes its non-operating position for moving said supporting means relative to said stationary die to release the forged article from the latter.

8. In a forging machine, in combination, a hammer motor mounted for movement into and out of its operating position, means for moving said hammer motor as aforesaid, means for supporting an article to be forged in a position to be percussively acted on by said hammer motor when the latter is in its operating position, control means effective only when said hammer motor is in its operating position for effecting operation of said hammer motor, and means effective only when said hammer motor has been moved away from its non-operating position and controlled by said moving means for supplying cooling fluid to said supporting means for cooling the adjacent portions of the article during the forging operation.

9. In a forging machine, in combination, a hammer motor for effecting its forging function with a percussive action, means for moving said hammer motor into and out of its operating position, means for supporting an article to be forged in a position to be percussively acted on by said hammer motor, control means effective only when said hammer motor is in its operating position for effecting operation of said hammer motor, and means for supplying cooling fluid to said supporting means for cooling the supported portions of the article during the forging operation, and including fluid supply control means controlled by said motor-moving means and effective to effect cooling fluid supply only when said hammer motor has been moved away from its non-operating position.

10. In a forging machine, in combination, a hammer motor for effecting its forging function with a percussive action, means for moving said hammer motor into and out of its operating position, means for supporting an article to be forged in a position to be percussively acted on by said hammer motor, control means effective only when said hammer motor is in its operating position for effecting operation of said hammer motor, and means for supplying cooling fluid to said supporting means for cooling the supported portions of the article during the forging operation, and including fluid supply control means controlled by said motor-moving means and effective to effect cooling fluid supply only when said hammer motor has been moved away from its non-operating position, said motor-moving means, said control means and said cooling fluid supply means having a common operating element for effecting motor movement, motor operation and cooling fluid supply in a predetermined sequence.

11. In a forging machine, in combination, a forging hammer, a die member for supporting an article to be forged in a position to be operated upon by said forging hammer, an element extending into said die member and threadedly connected to said article for holding the latter in said die member during the forging operation, passage means extending into said element to a point adjacent its threaded connection to said article, and means for supplying a cooling fluid to said passage means.

12. In a forging machine, in combination, a forging hammer, a die member for supporting an

article to be forged in a position to be operated upon by said forging hammer, an element extending into said die member and threadedly connected to said article for holding the latter in said die member during the forging operation, said element movable relative to said die member for ejecting the article therefrom after the forging operation has been performed, means for cooling said element, means for rotating said element to at least partially release the threaded connection between the latter and the article after the forging operation has been performed, and means for moving said element relative to said die member for releasing the article therefrom.

13. In a forging machine, in combination, a fluid actuated hammer motor, means for delivering operating fluid to said motor, valve means for controlling the flow of operating fluid through said fluid delivering means, means for supporting an article to be forged in a position to be percussively actuated by said hammer motor, means for delivering cooling fluid to said supporting means to maintain portions of the article cool during the forging operation, valve means for controlling the flow of fluid through said cooling fluid delivering means, and means for operating both of said valve means including an operating element common to both valve means for effecting operation thereof in a predetermined sequence, said common operating element being operative to effect an opening of said cooling fluid valve means always before opening of said operating fluid valve means and to effect a closing of said cooling fluid valve means only after said operating fluid valve means is closed.

14. In an apparatus of the character described, the combination comprising a stationary forging die member for supporting an article to be forged and having an opening for receiving the article, an element extending freely into said opening in said die member and to which the article is secured for holding the article in forging position in said die member, means for actuating said element to at least partially release it from the article while the latter remains supported thereby, and means for thereafter moving said element bodily relative to said die member for releasing the forged article from said die member.

15. In a forging machine, in combination, a base frame, a forging hammer supported by said base frame for movement in planes extending transversely thereof between operating and non-operating positions, means for moving said forging hammer on said base frame, a die member for supporting an article to be forged in a position to be operated upon by said forging hammer, an element extending into said die member and movable relative to the latter for ejecting the forged article, a lever engageable with said element for moving the latter relative to said die member, and a cam carried by said hammer moving means and engageable with said lever when said hammer moving means is actuated to move said hammer toward its non-operating position for moving said lever to effect an ejection of the article.

16. In a forging machine, in combination, a hammer motor, a movable die percussively actuated thereby, a cooperating relatively stationary die adapted to receive an article to be forged, means for moving said hammer motor into and out of its operating position with respect to said stationary die, means for supporting the article to be forged with respect to said stationary die

11

in a position to be operated upon by said movable die when said hammer motor is in its operating position, control means actuated by an element of said motor moving means and automatically effective only when said hammer motor is in its operating position for effecting operation of said hammer motor, and means also actuated by an element of said motor moving means and automatically effective only when said hammer motor assumes its non-operating position for moving said supporting means relative to said stationary die to release the forged article therefrom, said motor-moving means, said control means and said article-releasing means having a common movable actuator for effecting, upon movement thereof in one direction, motor movement, interruption of motor operation and article release in a predetermined sequence.

17. In a forging machine, in combination, a hammer motor, relatively stationary die means for receiving an article to be forged, means for supporting said motor for bodily lateral movement along a rectilinear path at right angles to the longitudinal axis of said hammer motor into and out of aligned operating position with respect to said die means, means for moving said motor as aforesaid, and means actuated by an element of said motor moving means and automatically effective only when said hammer motor has been moved into its operating position into alignment with said die means for effecting operation of said motor.

18. In a forging machine, in combination, a hammer motor, relatively stationary die means for receiving an article to be forged, means for supporting said motor for movement along a rectilinear path at right angles to the longitudinal axis of said hammer motor into and out of its operating position with respect to said die means, means for moving said motor as aforesaid, means actuated by an element of said motor moving means and automatically effective only when said hammer motor has been moved into its operating position for effecting operation of said motor, and means also actuated by an element of said motor moving means and automatically effective only when said hammer motor has assumed its non-operating position to move the forged article from said die means.

19. In a forging machine, in combination, die means, a rotatable work holder having a threaded portion to which an article to be forged is adapted to be threaded secured for holding the article in forging position with respect to said die means, and means for rotating said holder with respect to the forged article while the latter remains stationary as regards rotation with respect to said die means for at least partially unthreading the holder portion from the article while the article remains supported by the holder.

20. In a forging machine, in combination, die means, a rotatable work holder having a threaded portion to which an article to be forged is adapted to be threaded secured for holding the article in forging position with respect to said die means, means for rotating said holder with respect to the forged article while the latter remains stationary as regards rotation with respect to said die means for unthreading the holder portion from the article while the article remains supported by the holder, and means for moving said work holder axially relative to said die means to move the forged article from the latter.

21. In a forging machine, in combination, a die for receiving an article to be forged, an ejector

12

element movable relative to said die and engageable with the article for supporting the latter with respect to said die during the forging operation, means for supplying cooling fluid internally of said ejector element when the latter is in article supporting position, and means for moving said ejector element relative to said die upon completion of the forging operation to release the forged article from said die.

19. 22. In a forging machine, in combination, a die for receiving an article to be forged, an ejector element movable relative to said die and engageable with the article for supporting the latter with respect to said die during the forging operation, means for supplying cooling fluid internally of said ejector element when the latter is in article supporting position, means for moving said ejector element relative to said die upon completion of the forging operation to release the forged article from said die, and control means for said cooling fluid supply means coordinated with said ejector-element-moving means for interrupting flow of cooling fluid to said ejector element when the latter has assumed its article releasing position.

25. 23. In a forging machine, in combination, die means, a rotatable work holder having a connection to which an article to be forged is adapted to be coupled for holding the article in forging position with respect to said die means, and means for rotating said holder with respect to the forged article while the latter remains stationary as regards rotation with respect to said die means for at least partially uncoupling said holder-connection from the article while the article remains supported by the holder.

24. 24. In a forging machine, in combination, die means, a rotatable work holder having a connection to which an article to be forged is adapted to be coupled for holding the article in forging position with respect to said die means, means for rotating said holder with respect to the forged article while the latter remains stationary as regards rotation with respect to said die means for at least partially uncoupling said holder-connection from the article while the article remains supported by the holder, and means for moving said work holder axially relative to said die means to release the forged article from the latter.

50. 25. In a forging machine, in combination, a die member for receiving an article to be forged, an element extending into said die member and coupled to the article for holding the latter in said die member during the forging operation, passage means extending into said element to a point adjacent its coupling with the article, and means for supplying a cooling fluid to said passage means.

60. 26. In a forging machine, in combination, a die member for receiving an article to be forged, a rotatable element extending into said die member and coupled to the article for holding the latter in said die member during the forging operation, said element movable relative to said die member for ejecting the article therefrom after the forging operation has been performed, means for cooling said element, means for rotating said element to at least partially uncouple the latter from the forged article, and means for moving said element relative to said die member for releasing the forged article therefrom.

70. 27. In a forging machine, in combination, a hammer motor, a movable die percussively actuated thereby, a cooperating relatively stationary die adapted to receive an article to be forged,

means for moving said hammer motor into and out of its operating position with respect to said stationary die, control means for effecting operation of said hammer motor only when the latter is in its operating position, and means coordinated with and actuated by said moving means and automatically effective only when said hammer motor has assumed its non-operating position for releasing the forged article from said stationary die.

WADE H. WINEMAN.
